METHOD OF LOCATING AND REPAIRING
SUCTION STRAINER DAMAGES IN WELLS

Ernest Kerman, Kfar-Saba, Palestine

Application July 5, 1938, Serial No. 217,441
In Palestine July 7, 1937

5 Claims. (Cl. 166—21)

The purpose of my invention is to furnish a method of locating and repairing suction strainer damages in wells. My method is characterized by the inflation of an inflatable flexible endless tube (or tubes) encircling the suction pipe or other pieces of pipe or other objects; this inflatable flexible tube (or tubes) introduced into the well is inflated and pressed against the wall of the strainer. Water is then pumped through the suction pipe and if the pumped water is free of sand, the inflatable flexible tube covers the place of damage. If the pumped water is not free of sand, the place of damage is not covered and the inflatable flexible tube must be shifted until the place of damage is found.

After the damage is located the endless tube or tubes made of rubber, leather, impermeable canvas or other materials may be inflated by substances such as paraffin, plaster of Paris or cement mixed with water or bees-wax or the like, in a liquid form which subsequently solidify in order to effect a permanent repair.

The suction strainers generally used consist of an iron pipe provided with a large number of holes. The pipe is covered on its exterior by a dense netting of copper wire (galvanized). This netting is wrapped in sheet form around the pipe and soldered to it. Damages may sometimes be caused by mechanical injury by sharp or pointed objects which fall into the strainer in the well. In their fall these objects strike the inside walls of the strainer, piercing the netting of copper wire covering the holes of the strainer. Thus damages are caused to the strainer preventing it from fulfilling its functions and allowing sand to be drawn through the strainer. The well is thus gradually undermined since the sand is drawn through the strainer from the bottom and the sides of the well, and may in time collapse causing all sorts of accidents. The installation of a new strainer in place of the injured one means additional expense and a considerable loss of time.

In my method inflatable flexible tubes are introduced into suction strainers from above, encircling the suction pipe by means of rods, wires, ropes and the like. They are inflated and deflated in the suction strainer in such a manner that different parts of the suction strainer are alternately used for straining water from the sand, thereby enabling the worker to ascertain the depth at which the strainer is damaged. Subsequently a tube is inflated over the damaged portion of the strainer, or two tubes encircling a suction pipe, any pipe or other objects are in-

flated above and below the damaged portion. Thus, a minimum of the portion of the strainer is isolated (therefore not utilized for straining water) and the damage is covered and permanently repaired.

My method applied in three different ways will be further explained with reference to the accompanying drawings in which Figs. 1, 2 and '3 are vertical cross-sections of suction pipe and strainer.

In Fig. 1 a portion of a strainer 1 is shown. The suction pipe 2 is shown with an inflatable flexible endless tube 3, encircling the bottom end thereof. In order to do this suction pipe 2 is removed from the strainer 1, tube 3 being drawn tightly onto the suction pipe 2. It is then replaced into the strainer 1. The tube 3 encircling the suction pipe 2 is connected to a compressor or a pump by means of a tube 4 which is provided with a manometer 5. If liquids are used to inflate the tube it is sufficient to pour a liquid of higher density than water into tube 4 (by means of a funnel.) Examples of such liquids are salt water, nitrates dissolved in water and the like. It is possible to hold the opening of tube 4 a few meters above the water level in the well, and to pour the liquid into it by means of a funnel. The difference of the water levels inside and outside the tube 4 is sufficient to inflate tube 3. The tube 3 is inflated with air, water or any suitable gas or liquid and is so enlarged by inflation that it completely and tightly encircles the bottom end of pipe 2 and is pressed against the walls of the strainer 1 as shown in Fig. 1. If the pump is set in motion it pumps only the water coming through that part of the strainer which is below the inflated tube 3. If after a short period of pumping, the water is found to be free of sand, it is understood that the damage lies above the inflated tube 3. If the pumped water is not free of sand, it indicates that the damage lies below the inflated tube 3. In the latter case, the operation must be repeated lowering the tube 3 deeper into the well, and so on until the damage is located over the inflated tube 3. The suction pipe 2 is disconnected from the pump and lengthened by screwing an additional piece of pipe on its upper extremity. The bottom of the lengthened suction pipe 2 and therefore tube 3 are now deeper in the well.

Another application of my method is illustrated in Fig. 2. After disconnection and removal of suction pipe 2, two pipes 6 and 7 are introduced into the strainer and supported from above by wires or other means, whereupon the

suction pipe 2 is fitted again in the well. Pipes 6 and 7 have been constructed so that pipe 6 is of a smaller diameter than pipe 7 and easily passes through it. Encircling the ends of pipe 5 7 are two inflatable flexible tubes 8 and 8' to which is connected a long and thin tube 4" which leads out of the strainer to a compressor and manometer 5". Likewise encircling pipe 6 10 are two inflatable flexible tubes 9 and 9' to which is connected a long and thin tube 4' which leads out of the strainer to a compressor and manometer 5'. Another inflatable bag 10 which is introduced into pipe 6 is connected to a long and thin tube 4" which leads out of the strainer to a compressor and manometer 5". Now tubes 9, 9' and bag 10 are inflated, shutting off all contact between the water above and below the pipe 6, inflatable tubes of pipe 7 being as yet not inflated.

The pump is set in motion and if the water is 20 not free of sand, it is understood that the strainer is damaged above the pipe 6. Now we inflate tubes 8, 8' of pipe 7 and if the pumped water is not free of sand, it is understood that the damage is not between the tubes 8 and 8'. Then we deflate tubes 8 and 8' of pipe 7 and move the latter up or down, repeating the process until we obtain water free of sand thus indicating that the damage is now located and is between the tubes 8 and 8'. 25 Now the bag 10 of pipe 6 is deflated and if the pumped water remains clear of sand, it means that there are no damages under pipe 7. Then the tubes 9 and 9' of pipe 6 are deflated and pipe 6 is withdrawn from the strainer. The 30 pipe 7 which, as explained above, has been manoeuvred over the damaged portion of the strainer and tubes 8 and 8' inflated, thereby shutting off the flow of sand into the strainer, must remain in the strainer permanently. 35 Endless tubes 8 and 8' may be inflated by substances such as paraffin, plaster of Paris or cement mixed with water or bees-wax or the like, in a liquid form which subsequently solidify. Thus the damage which is located between tubes 40 8 and 8' is repaired by the isolation of the damaged place as described.

Fig. 3 shows an alternative method of repairing the damage as described with reference to Fig. 2 after the damage has been located according to the method described in the preceding paragraphs. In Fig. 3 we see pipe 7' which fulfills the same functions as pipe 7 in Fig. 2 but here fulfills other functions as well, as will be subsequently shown.

55 This pipe 7' is encircled by two pairs of tubes 9" and 9'" and 11 and 11'. The exterior of pipe 7' between the inner pair of tubes 11 and 11' is covered with a film 12 of a solid substance such as paraffin, bees-wax, plaster of Paris or any 60 other like substances which may subsequently be melted or dissolved. The space between this film 12 and the strainer 1 is filled, by means of a tube introduced from above, with concrete or like substance, the pipe 7' and the film 12 being 65 provided with a hole or holes for this purpose.

After the film 12 has been melted or dissolved by pouring hot water into strainer 1, by electric heating or other means, the inflated tubes are deflated, pipe 6 and all its accessories, are withdrawn the damaged place being covered by a solid film 13.

In case the solid film 13 is very thin, it may be reinforced by a metal cylindrical sheet 15 which was provided above before the pipe 7' was 75 introduced into the strainer.

Between the lower pair of tubes 9'" and 11 as well as the upper pair 9" and 11', sand or like substance mixed with water may be poured in from above by means of tubes. This is done before the cement is poured into space 13. 5

The water of the above mixture percolates through the strainer 1 into the strata surrounding the strainer 1 causing the sand to pack together tightly. This prevents the cement from running out into the other parts of the strainer. 10

The above description contains several variations of the method which I have invented. But it must be understood that many more variations of this method are possible. The method is essentially based upon the utilization of any 15 number of inflatable flexible endless tubes which are introduced into wells encircling a suction pipe, other pipes or other objects, and which are then inflated.

• In my method I used a device essentially consisting of a support upon which one or more inflatable flexible tubes are mounted or upon which is drawn any inflatable material. 20

These tubes or inflatable material are connected to compressors by means of thin tubes made 25 of rubber or any other substance, and thus inflated or filled with gas or liquids which subsequently solidify.

The support may have the form of a piece of metal pipe, an empty prism with any number of 30 faces, a cylinder, a barrel and the like made of wood, metal or any convenient material. The tubes or inflatable material are made of rubber, leather, stuff and the like.

The thin tube can be connected to the inflatable flexible tube or the inflatable material from the inside of the support through a hole made into the support. 35

Fig. 4 shows a device in which the cylindrical support is encircled by an inflatable flexible tube. 40

Fig. 5 shows a vertical cross-section of the device of Fig. 4.

Fig. 6 shows another device in which inflatable material is drawn upon a cylindrical support.

Fig. 7 shows a vertical cross-section of the 45 device of Fig. 6.

The device of Fig. 4 is composed of an inflatable flexible tube 16 mounted on a piece of pipe 17 which is inflated by means of a thin tube 18. This inflatable flexible tube 16 when inflated is 50 pressed against the walls of the strainer 9. The device of Fig. 6 is composed of a piece of pipe 20 which serves as a support and upon which is drawn rubber or other inflatable material bound by iron hoops or rings 22 to the support 20 on 55 both ends. This inflatable material 21 is connected to a thin pipe 23 through the interior of the support 20 in which a hole 24 is made.

Having thus described my invention, what I claim is:

1. A method of repairing damages inside strainers in wells characterized by the use of inflatable casings surrounding hollow bearers, said casings being connected to thin tubes leading above and out of strainers, said casings being shifted inside the strainers until the damaged portions are covered by the casings which are then inflated by means of said tubes with liquids or pastes which subsequently solidify. 65

2. A method of repairing damages inside 70 strainers in wells characterized by the use of inflatable casings surrounding hollow bearers, said casings being connected to thin tubes leading above and out of strainers, said casings being shifted inside the strainers until the damaged 75

portions are isolated between two such casings by inflation, the casings being inflated by means of said tubes with liquids or pastes which subsequently solidify.

5 3. A method of repairing damages inside strainers in wells characterized by the use of inflatable casings surrounding hollow bearers, said casings being connected to thin tubes leading above and out of strainers, said casings being shifted inside the casings until the damaged portions are covered by the casings which are then inflated by means of said tubes with liquids or pastes which solidify, but can subsequently be melted or dissolved.

10 15 4. A method of repairing damages inside strainers in wells characterized by the use of

inflatable casings surrounding hollow bearers, said casings being connected to thin tubes leading above and out of strainers, said casings being shifted inside the strainers until the damaged portions are isolated between two such casings by 5 inflation, the casings being inflated by means of said tubes with liquids or pastes which solidify but can subsequently be melted or dissolved.

10 5. A method of repairing strainer damages in wells by isolating damaged portion of strainer 10 between two inflatable packers mounted on a hollow bearer subsequently injecting cementing material by means of tubes piercing the bearer into the space between the two packers, the strainer and the bearer. 15
